DOUCHE NOZZLE

Joseph Emlich and Raymond Espelage,
Cincinnati, OhioApplication September 21, 1931
Serial No. 563,987

1 Claim. (Cl. 128—241)

Our invention relates to douche nozzles, and particularly to a vaginal douche nozzle for use with a douche bag in which the pressure of the solution is induced by the static head of the 5 solution within the bag.

It is an object of our invention to provide a nozzle which may readily be taken apart for sterilizing, and which has a sufficiently large 10 opening within the body of the nozzle to permit a cleaning brush to be used in cleaning the internal parts of the nozzle.

Another object of our invention is the provision of a nozzle having a hooded portion shaped to correspond with the body opening within 15 which the nozzle is to be inserted.

It is our object to provide a nozzle which may readily be manipulated for an irrigating douche in which the solution is retained for a desired interval. Another object is the provision of a 20 nozzle which will permit the return flow of the solution together with any discharged matter removed from the parts irrigated without likelihood of stoppage of the return flow.

Specifically, it is our object to provide a nozzle 25 for a vaginal syringe in which the person using the syringe may retain a desired amount of fluid within the vagina at a desired pressure consistent with the static head of liquid in the douche bag.

The above objects and other objects to which 30 reference will be made in the ensuing disclosure, we accomplish by that certain combination and arrangement of parts of which we have illustrated a preferred embodiment.

Referring to the drawing: 35 Figure 1 is a side elevation of the internal part of the nozzle.

Figure 2 is a plan view of the nozzle hood.

Figure 3 a sectional view taken along the line 3—3 in Figure 2.

40 Figure 4 is a sectional view taken along a line extending longitudinally through the nozzle assembly.

The nozzle is composed of an inner spray tube 1 having a passage 2 extending throughout its 45 length. The tip of the tube is rounded as indicated at 3, and the discharge openings 4 are arranged in an annular groove 5 which prevents any tendency of the discharge orifices being blocked up by pressure of the parts of the body 50 being irrigated, against the openings.

The spray tube has a large circular flat flange 6 formed integrally therewith, which flange has a discharge opening 7 which extends through a tubular projection 7a on the rear face of the 55 flange. There are bayonet lugs 8 also formed integrally with the tube.

The hood 9 for the spray tube is formed with an annular recessed channel 10 within which the flange 6 fits, being held therein by the engagement of the bayonet lugs 8 against spaced cam 60

surfaced bosses 11 which are formed on the inner side of the hood 9. The shape of the hood 9 is preferably that of a bell elliptical in cross section, so as to contact with the walls of the vagina so that there will be no leakage.

When the spray tube 1 is inserted within the hood and the douche is used, the cleaning fluid passes through the central tube out through the openings 4. The irrigation fluid is then returned through the annular opening 12 between the internal tube and the hood, and passes out through the tubular projection 7a. It will be obvious that pressure may be built up by placing the finger over the end of the tube 7a. When the parts have been dilated sufficiently, the finger 75 may be removed and the solution, together with any discharge with which the cleaning fluid is contaminated, may be flushed out.

A washer 10a is used between the flanges 6 and 10 to make a leak proof joint.

The assembly may be readily taken apart by turning the flange 6 so as to release the bayonet lock. As to size it will be obvious that for different types, or cleaning and sterilizing different parts of the body, the shape and size of the nozzle may be changed. When a nasal spray is desired, the size of the hood should be such as to accommodate itself to the shape of the opening in the nostril. So, for aural spraying, the size of the hood will be even smaller than for a nasal 90 spray. For colon irrigation, the hood will be larger to accommodate itself to the opening of the rectum.

The nozzle may be made of any desired material such as hard rubber, bakelite, or the lighter 95 metals, such as aluminum.

Having thus described our invention, what we claim as new and desire to secure by Letters Patent is:

A douche nozzle comprising a drain casing 100 with open inner and outer ends and a nozzle tube extending through said casing ends and having an annularly extended flange fitting across the outer end of the casing, with a drain opening in said flange, the oppositely facing 105 walls of the tube and casing, interiorly of the casing, having means coacting to clamp the flange across the end of the casing upon turning the tube and flange relatively to the casing, said means having a passage for flow through the 110 casing.
